CLAIM

The ornamental design for a chin mounted patient interface frame, as shown and described.

DESCRIPTION

FIG. 1 is a front perspective view of an embodiment of a patient interface frame according to our new design;

FIG. 2 is a front elevational view of the patient interface frame shown in FIG. 1;

FIG. 3 is a rear perspective view of the patient interface frame shown in FIG. 1;

FIG. 4 is a top plan view of the patient interface frame shown in FIG. 1;

FIG. 5 is a bottom plan view of the patient interface frame shown in FIG. 1;

FIG. 6 is a left side elevational view of the patient interface frame shown in FIG. 1; and,

FIG. 7 is a right side elevational view of the patient interface frame shown in FIG. 1.

The portions drawn in broken lines are shown for illustrative purposes only and form no part of the claimed design.
